UNITED STATES PATENT OFFICE.

HENRY H. KRYGER, OF MINNEAPOLIS, MINNESOTA.

CYLINDER ROTARY SNOW-PLOW.

SPECIFICATION forming part of Letters Patent No. 707,121, dated August 19, 1902.

Application filed May 3, 1897. Serial No. 634,973. (No model.)

To all whom it may concern:

Be it known that I, HENRY H. KRYGER, a citizen of the United States, residing at Minneapolis, in the county of Hennepin and State of Minnesota, have invented new and useful Improvements in Cylinder Rotary Snow-Plows, of which the following is a full, clear, and exact description, reference being had to the accompanying drawings, which form a part 10 of this specification.

My invention relates to devices for removing snow from railroad-tracks; and it consists of the construction, combination, and arrangements of the parts or elements herein shown 15 and hereinafter described.

In the accompanying drawings, Figure 1 is side elevation of my plow complete; Fig. 2, a top view of flanger; Fig. 3, the automatic flanger-raiser. Fig. 4 is a wing of fan or 20 blower incased, also showing the annular saws of upper and lower sections of cylinders. Fig. 5 is a front view of fan or blower. Fig. 6 is a top view of the vertical cylinders. Fig. 7 represents auxiliary or extension cylinders; 25 Fig. 8, a section of Fig. 6, taken on the line $\alpha\alpha$. Figs. 9, 10, 11, and 12 are details.

Similar figures indicate similar parts throughout the several views, figure 1 being the car upon which my snow-plow is mounted 30 and by which it is carried; 2, the twin cylinders; 3, the fan; 4, the flanger, and 5 the engine that runs the fan and flanger.

The car 1 may be of any construction adapted to the purpose.

35 The twin cylinders 2 are mounted upon the forward portion of the car 1. They are secured to and revolved by shafts 6 6, which shafts incline from the perpendicular, their inclination being forward at an angle of from 40 ten to twenty degrees. The lower portions of these cylinders are smaller than the remaining portions, as will hereinafter be understood. They are provided upon their circumferential sides with open knives or cutters 7, 45 longitudinally secured thereto, which knives serve to cut the snow parallel therewith, with annular saws or having series of saw-teeth 8, which serve to cut the snow at an angle of ninety degrees thereto, and with carriers 9, 50 which serve to carry the disintegrated snow to the fan 3. These twin cylinders revolve in

opposite directions, as indicated by the arrows. (See Fig. 6.) Hence the disintegrated snow is carried through between them to the fan 3. Their shafts 6 6 are connected to and 55 revolved by incased gears and a driving-shaft, as shown in Fig. 6, or by beveled gears or sprocket wheels and chains; but as such devices are common and form no part of my invention I do not deem it necessary to give a 60 detailed description of the same herein.

The fan 3 is partly inclosed by the case 10, the front side of which is left open to admit the disintegrated snow thereto. It is provided with two openings 11 11. (Shown in Fig. 65 6 and again in dotted lines in Fig. 8.) These openings are located in its roof, one extending obliquely to the right and the other extending obliquely to the left. These openings are covered by valves or doors 11^a, which 70 valves are affixed to the shafts 12 12. These shafts in turn are provided with the gear-wheels 13 13, which serve to operate them and to open and close the valves 11^a. 14 is an intermediate gear-wheel, which simultaneously operates the gear-wheels 13 13. This gear-wheel 14 is provided with a shaft 15 and a hand-wheel 16, by means of which it is operated by the engine-driver. It will be seen that but one of the openings 11 can be employed at once and the same time, the one used being determined by the direction of motion of the fan 3, which fan is reversible and may be run in either direction, according to the direction in which it is desirable to throw 85 the snow. This is accomplished by reversing the engine which drives the fan in the usual manner of reversing motion. In Fig. 7 I show auxiliary or extension cylinders armed with cutters and carriers, which may be employed 90 where the snow is very deep. They are secured to the end of shafts 6 6 by means of set-bolts or their equivalents or may be bolted to the top end of cylinders 2. The flanger 4 (shown in Fig. 2) consists of an incased wheel 95 17, affixed to and revolved by a vertical shaft 18. It is provided at its periphery with teeth, their purpose being to cut the snow or ice from between the rails or track, while the radial arms 4^d serve as a fan to blow the 100 disintegrated snow off the track. It is secured to the floor of the car 1, and is raised

or lowered by means of the automatic flanger-raiser 19. The purpose of the flanger-raiser is to raise the flanger when passing a frog or crossing, its operation being as follows: The wheels 19^b strike the frogs or crossing-rails and in riding over the same raise the shaft and frame 19^c. This in turn (through the operation of the rod 20) raises the arm 21, causing it to contact with the electrically-connected magnet 22. This in turn creates a magnetic current which actuates the steam-valve 23, thereby letting steam into the cylinder 24, which depresses the piston and rod 25 and raises the flanger 4 to pass over the frog or crossing-rails.

The twin cylinders 22 are driven by an engine (not shown in the drawings) through the operation of its shaft 27, the sprocket-wheels 28, and the chain 29, while the fan 20 and flanger are driven by a separate engine 5 through the operation of its shaft 30, the sprocket-wheel 31, and the chain 32. The shaft 35, driven by the sprocket-wheels 28 and chain 29, rotates the twin cylinders 22 through the operation of the intermediate shafts 6.

The operation of my plow is as follows: The twin cylinders 2, contacting with a snow-bank and revolving rapidly, cut the snow by 30 means of their knives or cutters 7 and by the saw-teeth 8. The carriers 9 throw or carry the snow inward and between the cylinders 2 into the fan-case 10 therein. The fan revolving rapidly throws the disintegrated snow 35 to the right or to the left, as the case may be, out of the fan-case 10 to either side of the track.

Fig. 9 is a detached knife.

Fig. 10 is a detached snow-carrier.

40 Fig. 11 is a cross-section of snow-carrier, and Fig. 12 is a detached knife which may be affixed to the lower and smaller sections of the twin cylinders 22, so that they may cut as wide a path through the snow as their 45 upper portions. This knife 33 is shown attached in Fig. 8.

Having thus described my invention, what

I claim as new, and desire to secure by Letters Patent, is—

1. In a snow-plow, the combination of the 50 forwardly-inclined twin cylinders, rotating in opposite directions upon forwardly-inclined shafts operated by covered or incased gearing; open knives, affixed upon the said twin cylinders, adapted to cut the snow parallel therewith; other knives or saw-teeth affixed to, and extending laterally from the said cylinders, adapted to cut the snow at an angle to the said open knives; carriers, affixed to and rotatable with the said twin cylinders 55 60 adapted to carry the disintegrated snow from opposite directions inward and between them, and a partially-incased fan, revolving in the rear of the said twin cylinders; adapted to dissipate the disintegrated snow, and to force 65 it outward through chutes in its case, to either side of the track, substantially as shown and described.

2. The combination in a snow-plow having 70 revolving cylinders adapted to cut a path or passage therefor, and a revolving fan adapted to dissipate the disintegrated snow; of the automatically-controlled revolving flanger, substantially as shown and described.

3. In a snow-plow having a suitable frame 75 or support, the revolving twin cylinders 2 rotating in opposite directions, said cylinders being armed with the open knives 7 adapted to cut the snow parallel therewith, with the laterally-revolving saws 8 adapted to cut the 80 snow horizontally; and with the revolving carriers 9 adapted to carry the disintegrated snow from opposite directions between them; said cylinders being rotated by means of shafts, and gears, said shafts and gears being 85 inclosed or incased to shield them from the snow, substantially as shown and described.

In testimony whereof I have hereunto set my hand this 25th day of March, A. D. 1897. 90

HENRY H. KRYGER.

In presence of—

A. P. PETERSON,
ANNA MARBOE.
